United States Patent Office

Des. 181,349
Patented Nov. 5, 1957

181,349

DISPLAY STAND OR SIMILAR ARTICLE

Harve Ferrill, Chicago, Ill., assignor to Harve Ferrill & Company, Chicago, Ill., a corporation of Illinois

Application March 14, 1956, Serial No. 40,609

Term of patent 7 years

(Cl. D80—9)

Fig. 1

I claim:

The ornamental design for a display stand, or similar article, as shown and described.
